United States Patent Office

Des. 190,579
Patented June 13, 1961

190,579

ELECTRIC HAIR CLIPPER

Alfred W. Madl, Milwaukee, Wis., assignor to John Oster
Manufacturing Co., Milwaukee, Wis., a corporation of
Wisconsin

Filed Aug. 30, 1960, Ser. No. 61,959

Term of patent 14 years

(Cl. D22—5)

Fig. 1.

Fig. 2.

FIGURE 1 is a top perspective view of an electric hair clipper embodying my new design;

FIGURE 2 is a bottom perspective view thereof;

FIGURE 3 is a top plan view of the clipper;

FIGURE 4 is a side elevational view thereof; and

FIGURE 5 is a bottom plan view thereof.

The dominant features of my design reside in those portions thereof shown in solid lines.

I claim:

The ornamental design for an electric hair clipper, as shown and described.
